UNITED STATES PATENT OFFICE.

HARRY L. CAMP, OF LYNCHBURG, VIRGINIA.

BOX-STAY.

1,252,234.

Specification of Letters Patent.

Patented Jan. 1, 1918.

Application filed February 2, 1916. Serial No. 75,830.

To all whom it may concern:

Be it known that I, HARRY L. CAMP, a citizen of the United States, residing at Lynchburg, in the county of Campbell and State of Virginia, have invented new and useful improvements in Box-Stays, of which the following is a specification.

This invention relates to box stays or stays for strengthening and reinforcing boxes or packing cases, especially at the corners thereof, and it has for its object to produce a simple and improved device of the character described which may be easily and effectively applied to boxes or packing cases made of wood, fiber, paper or other material.

A further object of the invention is to produce a set of light and inexpensive, but strong and wear-resisting corner stays, and means whereby the said stays may be quickly and effectively applied to a box or packing case.

A further object of the invention is to produce a simple and improved set of corner stays, the same being initially connected together in such a fashion as to enable them to be quickly and effectively applied to a box or packing case of predetermined dimensions.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications may be made within the scope of the claims.

In the drawing,—

45 Figure 1 is a perspective view of one of the improved stays.

Fig. 2 is a perspective view showing a set of stays connected together by connecting wires.

50 Fig. 3 is a top plan view of a packing case to which the set of stays have been applied.

Fig. 5 is a bottom plan view of the same.

Fig. 5 is a top plan view similar to Fig. 3, but illustrating a slight modification.

55 Fig. 6 is a perspective detail showing a

modified construction of one of the corner stays.

Corresponding parts in the several figures are denoted by like characters of reference.

The improved stay, as seen at A, consists 60 of an angular trough having side walls 15 and end walls 16, the same being preferably formed of material such as sheet metal by any well known process of pressing or stamping, whereby said stay may be formed 65 in a single integral piece. The side walls 15 are preferably at right angles to each other, while the end walls 16 are formed at right angles to the side walls so as to lie in planes that are substantially parallel. The 70 end walls 16 are provided with apertures 17 for the passage of the connecting wires. The stays are to be made of suitable length to enable them to be fitted on boxes or packing cases of predetermined dimensions. 75

The stays A are provided in sets of four adapted to be mounted on the four corners of a square or rectangular box or packing case B with the end walls 16 abutting on the top and bottom faces of such box or packing case. The stays are connected together at their lower ends by wires 18 extending diagonally across the bottom face of the box. The upper ends of the stays are connected together in pairs by wires 19, each of said 85 wires serving to connect together the two stays A adjacent to one side edge of the box, and the two wires connecting together in pairs the stays at opposite sides. As seen in Fig. 2, the wires 18 and 19 are assembled 90 with the stays by inserting the ends of the wires through the apertures 17 and then twisting the same, the stays being thus assembled together in sets prior to their application to the boxes or packing cases for 95 which they are intended.

It is obvious that the wires 18 should be of such length that when the stays are applied to the corners of the box, the said wires will be drawn taut. The top wires 19 100 may then be intertwined, as seen at 20 in Fig. 3, provided that said top wires are of a length to permit their looped portions to overlap sufficiently for the introduction of a tool, such as an ordinary wire nail, whereby they may be twisted together; if the wires 19 are not of sufficient length to permit their looped portions to be overlapped they may be drawn tightly together by means of a tie wire, as seen in Fig. 5, at 21. 110

In Fig. 6 of the drawing there has been shown a slightly modified construction of one of the corner stays, whereby the said stay, here designated by S, is grooved or 5 corrugated, the grooves or corrugations, designated by 23, having been shown as being formed longitudinally with respect to the stay, although it will be understood that they might be formed transversely or di- 10 agonally. The grooves or corrugations serve to stiffen and reinforce the stay which for this reason will form a stronger and more effective reinforcement for the box to which it is applied.

15 It will be seen that a set of stays constructed and applied as herein shown and described will not only serve to reinforce the corners of the box or packing case, but that they will also serve to prevent either the top or the bottom of the box or case from being surreptitiously opened or removed, thereby protecting the contents during ship- 0 ment.

Having thus described the invention, 5 what is claimed as new, is:—

1. A box protecting device consisting of a set of four corner stays having angularly

disposed side walls and upper and lower end walls, bottom wires whereby the lower end walls of diagonally opposed stays are permanently connected together, and top wires whereby the upper end walls of the stays disposed in parallel planes are connected together. 30

2. The combination with a packing case 35 of a set of four corner stays having angularly disposed side walls and upper and lower end walls, the end walls being provided with apertures, bottom wires engaging and permanently connected with the lower end walls of diagonally opposed stays, top wires terminally engaging and connected with the apertured upper end 40 walls of stays located in parallel planes at opposite sides of the box, and means whereby the looped portions of the top wires are drawn taut and connected together. 45

In testimony whereof I affix my signature in presence of two witnesses.

HARRY L. CAMP.
